INVENTOR:

BY *Bohdan Pantofliček* HIS ATTORNEY.

UNITED STATES PATENT OFFICE.

BOHDAN PANTOFLÍČEK, OF PILSEN, CZECHOSLOVAKIA.

PERCUSSION FUSE.

Application filed September 3, 1924, Serial No. 735,611, and in Czechoslovakia September 11, 1924.

My invention relates to that class of percussion fuses for projectiles of that class in which the fuse normally held in inoperative position by safety devices is released in the 5 very last moment of the flight of the projectile by forces set up directly before the projectile hits the target.

My invention consists in that the striker is connected with a disc hitting on the target. 10 The result of this arrangement is that the striker together with the disc have so small a mass that the safety device may be comparatively light. Owing to the small mass of the 15 striker and the disc and the relative small resistance of the diaphragm 4 of the safety device the fuse is rendered extremely sensitive.

This invention is illustratively exemplified in the accompanying drawing in which, 20 Figure 1 is a longitudinal sectional view of a percussion fuse. Figure 2 is a similar view of a slightly modified form of construction; and Figures 3 and 4 are views of still further modifications of my invention.

25 In the annexed drawing four embodiments of my invention are shown diagrammatically in axial section. In all the figures like parts are marked with the same numerals of reference.

30 In the drawings, 1 is the detonating pellet, 2 is the striker, 3 is the disc which is exposed to the direct impact when the projectile hits the target, 4 is the safety device holding the disc 3 in the safe position and 35 releasing the same only when the projectile hits the targets. 5 is a cover plate covering the pellet and can be perforated only when the projectile strikes the target whereupon the striker causes the pellet to detonate as the relative movement of the striker and pellet is continued. 6 is a spring acting on the pellet and 7 is the body of the fuse.

In the embodiment shown in Fig. 1 the disc 3 is rigidly connected to the striker 2. 45 The inner part of the striker is so guided that the striker can move only axially. The pellet 1 is freely guided in the fuse body so that the axes of the pellet and of the striker are in alignment. The spring 6 tends to hold the pellet in its uppermost position. The mass of the disc 3 and the 50 striker 2 being comparatively small the safety device may be comparatively light so that when the projectile strikes the target

this device offers only a slight resistance 55 thereby rendering the fuse very sensitive. An accidental perforation of the pellet 1 is prevented by a cover plate 5 which can be perforated only by a heavy impact such as would be exerted on the striker when the 60 latter after breaking the safety device 4 is thrown against the pellet when the projectile strikes the target. As a consequence of this arrangement the cover plate 5 is first 65 perforated and then the pellet 1. If by accident the striker 2 is thrown with insufficient velocity against the cover plate 5 of the pellet 1 this cover plate will be forced back together with the pellet against the action of the spring 6 without being injured. 70 By properly selecting the thickness of the cover plate 5 and the strength of the spring 6 any desired amount of sensitiveness and safety of the fuse may be obtained. On firing the projectile the pellet recedes owing to 75 inertia compressing the spring 6; and if the latter is of sufficient strength to resist this pressure it follows that the plate 5 must be of a relatively greater thickness.

In the constructional form shown in Fig. 80 2 the pellet 1 is guided in a sleeve 9 mounted in the fuse body 7. This sleeve is provided with inturned tongues 8 holding the pellet in its uppermost position. These tongues are so proportioned that they can withstand 85 the strain put on them owing to the inertia of the pellet on firing the projectile but are broken or bent outward before the cover plate 5 is perforated when the striker strikes against the plate with a comparatively low 90 speed. Only when the projectile strikes the target and consequently the striker is thrown with great vehemence against the pellet is the plate 5 perforated and then the striker causes the pellet 1 to detonate.

In the constructional form shown in Fig. 95 3 the pellet 1 actuated by the spring 6 is maintained in its innermost position by a locking pin 11 which is held in locking position by a plug 10 acted upon by a spring 12. If desired a transverse pin 13 may be provided passing through the locking pin 11 and the plug 10. Thus the fuse is perfectly safe. On firing the projectile first the plug 10 recedes owing to inertia shearing off the transverse pin 13 if used and compressing the spring 12. The locking pin 11 after being released brings the pellet 1 under the influence of the spring 6 which forces it to its 100 105

upper position, as illustrated in Figure 1.

Figure 4 shows the fuse in the safety position for manipulation of the fuse. The pellet 1 is held in the lowermost position by the tongues 15. If during loading of the weapon or through inadvertence the safety device 4 is destroyed, nevertheless the striker 2 cannot reach the pellet and cannot detonate the same. But this safeguarding 10 by means of the tongues 15 is released when the weapon is fired. The sleeve 14 is movably mounted in the fuse body 7. Upon firing, the sleeve 14 is hurled backwardly relatively to the fuse body 7 and the tongues 15 are bent back or broken off. Thereupon the pellet 1 comes under the influence of the spring 6 in the uppermost position as shown in Figure 1. When thus the fuse has reached the target the position of the pellet 20 1 is exactly the same as shown in Figure 1.

What I claim is.

1. In a percussion fuse the combination with a fuse body, a striker and a disc fast on such striker, means for guiding axially the 25 striker and disc in the fuse body, a safety device adapted to hold the striker and disc in the safe position, a pellet adapted to cooperate with the striker and means for yieldingly supporting the pellet in the armed position, in the direction of said striker the said 30 striker and disc being small in mass and the safety device being light whereby the fuse is rendered very sensitive.

2. In a percussion fuse the combination 35 with a fuse body, a striker and a disc fast on such striker, means for guiding axially the striker and disc in the fuse body, a safety device adapted to hold the striker and disc in the safe position, a pellet adapted to cooperate with the striker and movable in the fuse body in alignment with the striker and means for yieldably supporting the pellet in the armed position, in the direction of 40 said striker the said striker and disc being small in mass and the safety device being light whereby the fuse is rendered very sensitive.

3. In a percussion fuse the combination 50 with a fuse body, a striker and a disc fast on such striker, means for guiding axially the striker and disc in the fuse body, a safety device adapted to hold the striker and disc in the safe position, a pellet adapted to cooperate with the striker, a cover plate interposed between the pellet and the striker and means for yieldably supporting the pellet in the armed position in the direction of said striker, the said 55 striker and disc being small in mass and the safety device being light whereby the fuse is rendered very sensitive.

4. In a percussion fuse the combination 60 with a fuse body, a striker and a disc fast on such striker, means for guiding axially the striker and disc in the fuse body, a safety device adapted to hold the striker and disc in

the safe position, a pellet adapted to cooperate with the striker and means for holding yieldingly the pellet in the safe position such means being adapted to operate in one direction under the action of inertia on firing and in the opposite direction under the action of the impact on striking the target, the said striker and disc being small in mass and the safety device being light whereby the fuse is rendered very sensitive. 75

5. In a percussion fuse the combination with a fuse body, a striker and a disc fast on such striker, means for guiding axially the striker and disc in the fuse body, a safety device adapted to hold the striker and disc 80 in the safe position, a pellet adapted to cooperate with the striker and means for holding yieldingly the pellet in the safe position such means consisting of resilient elements adapted to operate in one direction under the 85 action of inertia on firing and in the opposite direction under the action of the impact on striking the target, the said striker and disc being small in mass and the safety device being light whereby the fuse is rendered 90 very sensitive. 95

6. In a percussion fuse the combination with a fuse body, a striker and a disc fast on such striker, means for guiding axially the striker and disc in the fuse body, a safety device adapted to hold the striker and disc in the safe position, a pellet adapted to cooperate with the striker and means for holding yieldingly the pellet in the safe position, such means comprising a guide sleeve for the 100 pellet and inturned resilient tongues temporarily supporting the pellet and adapted to operate in one direction under the action of inertia on firing and in the opposite direction under the action of the impact on 105 striking the target, the said striker and disc being small in mass and the safety device being light whereby the fuse is rendered very sensitive. 110

7. In a percussion fuse the combination with a fuse body, a striker and a disc fast on such striker, means for guiding axially the striker and disc in the fuse body, a safety device adapted to hold the striker and disc in the safe position, a pellet adapted to cooperate with the striker and means for holding yieldingly the pellet in the safe position such means comprising a movable element adapted to normally hold the pellet away 115 from the striker and to release the pellet on firing and resilient means for moving the pellet when so released towards the striker whereby the pellet is brought into the path of the striker, the said striker and disc being small in mass and the safety device being 120 light whereby the fuse is rendered very sensitive. 125

8. In a percussion fuse the combination with a fuse body, a striker and a disc fast on such striker, means for guiding axially the 130

striker and disc in the fuse body, a safety device adapted to hold the striker and disc in the safe position, a pellet adapted to cooperate with the striker and means for holding 5 yieldingly the pellet in the safe position such means comprising a sleeve movable axially in the fuse body and provided with in-turned tongues normally holding the pellet away from the striker and a spring holding the pellet against the said tongues, the said 10 striker and disc being small in mass and the safety device being light whereby the fuse is rendered very sensitive.

In testimony whereof I affix my signature.

ING. BOHDAN PANTOFLIČEK.
